RIDGE TYPE VENTILATOR

Anton K. Whitaker, Cuyahoga Falls, Ohio, assignor to The Burt Manufacturing Company, Akron, Ohio, a corporation of Ohio

Application July 1, 1936, Serial No. 88,395

9 Claims. (CL. 98—42)

The present invention relates to long or ridge type ventilators for buildings. A ventilator of the ridge type has a number of advantages over individual or unit ventilators as it gives uninterrupted ventilation over the roof or roof section, whereas the unit type of ventilator concentrates ventilation at isolated spots and leaves intermediate areas unventilated. The ridge type ventilator is also more sightly than the unit type.

Ridge type ventilators have been known and used prior to the present invention, but earlier forms have had certain disadvantages and limitations which the present invention overcomes. One of the advantages of the ventilator shown and described herein is that outside currents of air striking the ventilator are directed within the interior thereof and are conducted through the ventilator so that a suction or siphoning effect is secured, increasing the efficiency of the ventilator. A further object of the invention is to provide for a vertically moving damper which increases the efficient length of the ventilator. Prior ventilators of this type have been equipped with dampers which move longitudinally as they are raised and lowered, thereby reducing the area of the opening in the building. The mechanism for raising and lowering the damper is also improved over previous designs.

Further objects of the ventilator are to improve upon the means for joining ventilator sections so that a long ventilator may be built up from individual sections. In the event that longer installations are required that would prevent the operation of the damper by a single device, the ventilator has been designed so that it may be divided into operative sections without breaking the symmetry of the installation.

Other objects and advantages are secured from the invention as will be apparent from the description and drawings, and it will be seen that changes and modifications may be made without altering the principles of the ventilator or changing its functions and purposes.

In the drawings in which the best known or preferred form of the invention is shown:

Fig. 1 is a side elevation of a unit of the ridge ventilator, one end being broken out to show the end closure and the other end being broken out on the line 1—1 of Fig. 2;

Fig. 2 is an end view looking into the unit from the right of Fig. 1;

Fig. 3 is a section at the closed end of the ventilator on the line 3—3 of Fig. 1;

Fig. 4 is a view showing the means of joining

or splicing two units, the section being taken on the line 4—4 of Fig. 5;

Fig. 5 is a horizontal section on the line 5—5 of Fig. 4;

Fig. 6 is a section on the line 6—6 of Fig. 7, showing the partition which is used in splicing two sections of the ventilator with individual dampers; and

Fig. 7 is a vertical section on the line 7—7 of Fig. 6.

The ventilator is adapted to any form or shape of roof, the support and attachment of the ventilator being changed to fit any type of roof encountered.

In the form shown the ventilator, which is formed in lengths or units, is mounted upon two oppositely positioned strips shown at 2—2 which are shaped to fit any roof construction to which the ventilator is adapted. These strips are located on opposite sides of the ventilation opening 3 leading from the interior of the building. At the end of the ventilator the metal may form the peak of the roof as shown at 4. The inner edges of the strips 2 are bent upwardly to form the vertical flanges 5 upon which the ventilator is supported. These flanges may be braced at convenient intervals by horizontal braces 7 and arched braces 8.

Along the sides of the ventilator are arranged the two parallel and oppositely positioned wind or storm bands 10 which are formed of sheet metal with the central vertical webs and inwardly inclined upper and lower edge portions 12 and 14, respectively. The windband is supported from the vertical flanges 5 by the rectangular straps 16 and inclined braces 17 which are secured by the bolts 18 which also form the attachments for the horizontal braces 7. It will be noted that the lower edge of the flange 14 is spaced from the roof an appreciable distance over the entire length of the ventilator to provide a longitudinal wind opening 15 on either side of the ventilator. In this respect the present type of ridge ventilator differs from and presents marked advantages over previous ventilators of this type as the construction is such that currents of air from outside the building will enter and be conducted through the ventilator so as to create a suction or aspirating effect and thus increase its effectiveness. The lower edge 15 may be maintained at the proper distance from the flanges 5 to permit the free entrance of external air currents by spacer sleeves 19 which are received over bolts 18 passing through the lower edge of the windbands and the vertical 55

straps 16. The windbands 10 are secured to the strips 2 by the bolts 18 which are received through the flanges 5 and the webs 12 of the windbands 10. The lower edge 15 of the windbands 10 is spaced from the roof an appreciable distance over the entire length of the ventilator to provide a longitudinal wind opening 15 on either side of the ventilator. In this respect the present type of ridge ventilator differs from and presents marked advantages over previous ventilators of this type as the construction is such that currents of air from outside the building will enter and be conducted through the ventilator so as to create a suction or aspirating effect and thus increase its effectiveness. The lower edge 15 may be maintained at the proper distance from the flanges 5 to permit the free entrance of external air currents by spacer sleeves 19 which are received over bolts 18 passing through the lower edge of the windbands and the vertical 55

flanges. The windband is stiffened along the lower edge by a reversely turned flange 20 and along the upper edge by a similar flange 21.

The upper edges of the windbands are spaced 5 apart along the top of the ventilator at some distance above the opening 3 to form the longitudinal discharge opening 24 and are braced by the horizontal straps 25 and by inverted arched straps 26, which latter form a convenient upper 10 limit or stop for the damper. The straps 25 form a convenient rest for a screen 28, if such is to be employed, screws 29 passing through the upper edge of the windband and into the edges of the screen.

15 The metal forming the vertical sides 5 of the ventilator is bent backwardly to form deflector strips which are indicated by the numeral 30. These deflector strips, in the form shown, are V-shaped and on their lower sides substantially parallel the lower edge portions of the windbands, being spaced therefrom to form the channels or passages 32 communicating with the passages 15 which conduct and direct the outside currents of air through the ventilator.

20 In former ridge ventilators, it has been the intention and object to prevent air currents from the exterior entering the ventilator. This is contrary to the principle and mode of operation of the present ventilator which admits the 25 external currents of air in very substantial quantities but guides and directs them after they enter the ventilator so as to increase the efficiency of the ventilator. For this purpose it will be observed that currents of air entering the openings 15 are directed by the deflectors 30 along the passages 32, from whence they move upwardly along the inner walls of the windbands and pass out through the opening 24 in the general direction of the arrows marked A.

30 The upward movement of these currents will create a suction or aspirating effect upon the air moving upward through the opening 3, such currents being noted by the arrows B. As these currents A and B meet around the lower edges 45 of the damper, the suction effect of the strong currents A will draw the air from the interior of the building upward through the opening 3 and out of the ventilator. The baffles or deflectors 30 also direct the incoming air currents 50 away from the opening 3 and there is no down draft.

The damper is indicated by the numeral 40 and is movable between its lower position, shown in dotted lines in Figs. 2, 3, 4 and 6, where it 55 rests upon the upper edges of the vertical flanges 5 and closes the opening 3, and its extreme upper position against the braces 26 (shown in full lines). It is moved to a greater or less extent by a chain or cord shown at 42. This 60 damper is superior to other dampers used in this type of ventilator because it moves in a vertical direction and does not shift longitudinally, being guided in its movement by rollers 44 attached to the sides of the damper and 65 moving in vertical trackways 45 attached to the underside of the edge portions 12 of the windbands and to the upper side of the deflectors 30.

The damper is of sufficient width to cover the 70 opening 3 and is formed with a central flattened trough or channel 48 by which the damper is supported upon rollers 50 arranged at convenient intervals in parallel rails 51 extending for a distance along the underside of the damper. The 75 rails 51 are connected at one end to an actuator-

ing link 52 to the lower end of which the chain 42 is attached. At one end of the damper, links 54 and 55 are connected to the rail 51 and the link 52, respectively, and are pivoted at 56 to the inside faces of the flanges 5. A supplemental or idle link 58 is provided at the other end of the damper. It will be seen that as the chain 42 is pulled, the rails 51 are elevated and the damper raised, the rolling contact with the underside of the damper permitting it to move in a vertical direction. The operation is easy and a long damper member may be moved with little exertion, nor is there any tendency for the damper-operating mechanism to bind at any point.

15 Rain, snow or debris entering the ventilator is intercepted directly by the damper and directed toward the sides of the ventilator, passing out onto the roof through the openings 15. By this improved construction it is not 20 necessary to provide a central ridge member in the top of the ventilator to make the device weatherproof, as in prior forms of ventilators of this type, and consequently freer passage of air is allowed through the ventilator.

25 To make the ventilator weatherproof at the end, a closure piece 60 is provided which fits around the windbands and is provided with a horizontal flange 62 which extends over the opening 3 and is provided with downwardly 30 flaring skirts 64 which direct water into the opening 15. An upstanding flange 65 is provided at the side of the piece 60 to prevent the overflow of water into the opening 3.

35 The ventilator which has been shown and described is made in unit lengths which may be joined together. The several units are spliced end to end as shown in Figs. 4 and 5. For this purpose the deflectors 30 on one unit are stepped back from the end of the unit to permit telescoping of the units. This is shown at 66 in Fig. 5. The side strips 2 and the windbands are overlapped and connected, the reversely bent reinforcing flanges being stepped back. A cover plate 67 is secured to and overlaps both dampers. In the event that an assembly of these units is not too long to permit the operation of the damper by a single mechanism, provision is made for joining the damper-operating mechanisms. In the form illustrated in Fig. 1, the 50 section will be added to the left of Fig. 1, the end piece 60 being removed and the splice made at that point. The added section will be provided with additional links 58, bar 51 and rollers. A tying link 69, broken off and shown in 55 dotted lines in Fig. 1, connects the bar 51 with the corresponding bar on the next adjacent section.

60 In the event the installation is too long to permit of the operation of the damper by a single operating device, or should separate damper controls be desired, it is necessary to provide a weatherproof joint at the division line between two sections. Such a device is shown in Figs. 6 and 7 and consists of a vertical wall 65 70, preferably formed of a two-ply metal, the lower edges of which are bent outwardly to provide cover plates 71 over the opening 3, extending for a sufficient distance to intercept rain between the ends of the dampers. Upright walls 70 72 prevent water from running off the plates into the opening and skirts 73 extend downwardly and overlap the side walls and deflector strips.

75 The ventilator secures the maximum efficiency 75

from the wind, but is storm and weatherproof throughout. The baffle or deflector strip 38, in combination with the spaced windband, gives a new and highly efficient mode of operation. Rain or snow entering the ventilator is deflected beneath the lower edge of the windband at the sides and ends and also at any division points between dampers. The vertical movement of the damper reduces to a minimum the amount of closure required at the end zone of the ventilator. The mechanism for raising and lowering the damper is simple and easy to operate. In fact, the mechanism operates so easily that as many as four ten-foot lengths may be operated by a single chain. The weight of the damper is always sufficient to close it when the chain is released. For fireproofness a fusible link may be inserted in the chain.

What is claimed is:

- 20 1. In a ventilator of the ridge type adapted to be mounted over a building ventilation opening, a casing composed of two parallel windbands spaced at their upper edges to provide a free discharge opening, walls within the casing on opposite sides of the building ventilation opening, a damper located in the casing and movable toward and from the ventilation opening in a vertical line, said damper being extended laterally to intercept rain entering the discharge opening and to direct it to the sides of the casing, the lower edges of the casing being spaced from the roof to permit free access of wind below the ventilation opening, deflectors below the ventilation opening to direct the wind against the inner walls of the casing and upwardly past the ventilation opening to the discharge opening, and means at the end of the casing to cover the ventilation opening sufficiently to prevent the entrance of rain at that point.
- 25 2. A continuous ventilator of the ridge type adapted to be placed over an elongated ridge opening, comprising two spaced parallel strips attached to the building at either side of a ridge opening, vertical walls rising from the inner edges of said strips, vertical parallel strips constituting storm bands located on opposite sides of the walls and spaced therefrom, the storm bands being provided with upper and lower inwardly directed inclined edges, inclined deflector members carried on the vertical walls and forming air directing channels with the lower edges of the storm bands, vertical end walls at the ends of the ventilator, a movable damper located over the ventilation opening and below the top of the storm bands, the ends of the damper being closely adjacent the end walls, and means to move the damper in a direct vertical path.
- 30 3. A continuous ventilator of the ridge type adapted to be placed over an elongated ridge opening, comprising two spaced parallel strips attached to the building at either side of a ridge opening, vertical walls rising from the inner edges of said strips, vertical parallel strips constituting storm bands located on opposite sides of the walls and spaced therefrom, the storm bands being provided with upper and lower inwardly directed inclined edges, inclined deflector members carried on the vertical walls and forming air directing channels with the lower edges of the storm bands, vertical end walls at the ends of the ventilator, a movable damper located over the ventilation opening and below the top of the storm bands, the ends of the damper being closely adjacent the end walls, and means to move the damper in a direct vertical path.
- 35 4. A continuous ventilator of the ridge type adapted to be placed over an elongated ridge opening, comprising two spaced parallel strips attached to the building at either side of a ridge opening, vertical walls rising from the inner edges of said strips, vertical parallel strips constituting storm bands located on opposite sides of the walls and spaced therefrom, the storm bands being provided with upper and lower inwardly directed inclined edges, inclined deflector members carried on the vertical walls and forming air directing channels with the lower edges of the storm bands, vertical end walls at the ends of the ventilator, a movable damper located over the ventilation opening and below the top of the storm bands.
- 40 5. In a continuous ventilator of the ridge type adapted to be placed over an elongated ventilation opening, comprising two spaced parallel strips attached to the building at either side of the ridge opening, vertical parallel storm bands extending the length of the ventilator and spaced on opposite sides of the strips, end walls on the ventilator, a movable damper over the ventilation opening located between the storm bands and extending from end wall to end wall, and means to move the damper in a direct vertical path.
- 45 6. In a continuous ventilator adapted to be placed over an elongated opening, comprising spaced parallel strips on either side of the opening, vertical walls rising from the strips and defining an elongated ventilation opening, vertical parallel storm bands extending the length of the ventilator on either side of the walls and spaced therefrom, inturned edge portions on the storm bands defining the outlet of the ventilator, and an elongated movable plate located in the space defined by the storm bands, the inturned edge portions and the upper edges of the vertical walls, said plate being adapted to operate as a damper and being of sufficient width to intercept rain entering the outlet opening and prevent it from entering the ventilation opening in any position of the damper.
- 50 7. In a continuous ventilator adapted to be placed over an elongated opening, comprising spaced parallel strips on either side of the opening, vertical walls rising from the inner edges of said strips and defining an elongated ventilation opening, vertical parallel storm bands extending the length of the ventilator on either side of the walls and spaced therefrom, inturned edge portions on the storm bands defining the outlet of the ventilator, a vertically movable elongated plate located between the outlet opening and the ventilation opening and constituting a damper, end walls on the ventilator, the ends of the damper lying adjacent the end walls, and means to move the damper in a direct vertical line.
- 55 8. A ventilator of the continuous ridge type adapted to be placed over an elongated building opening, comprising two parallel strips on opposite sides of the opening, vertical walls rising from the strips and defining the ventilation opening, vertically arranged storm bands on opposite sides of the ventilation opening but spaced to provide passages extending along the building between the lower edges of the storm bands and the roof, a movable damper over the ventilation opening below the upper edges of the storm bands and spanning the space between said vertical

walls and adapted to seat thereon in lowered position and inclined deflectors on the sides of the walls located within the passages and adapted to direct air currents which enter the ventilator from below along the inner surfaces of the storm bands.

9. A ventilator of the continuous ridge type adapted to be placed over an elongated building opening, comprising two parallel strips on opposite sides of the opening, vertical walls rising from the strips and defining the ventilation opening, vertically arranged storm bands on opposite

sides of the ventilation opening but spaced to provide passages extending along the building between the lower edges of the storm bands and the roof, inclined deflectors on the sides of the walls located within the passages and adapted to direct air currents which enter the ventilator from below along the inner surfaces of the storm bands and past the ventilation opening to create an aspirating effect at the ventilation opening, and a movable plate between the storm bands 10 constituting a damper.

ANTON K. WHITAKER.
